DECANTER

Robert E. Hennessy, Summit, N. J., assignor to
 National Distillers Products Corporation, New
 York, N. Y.

Application July 20, 1953, Serial No. 26,055

Term of patent 14 years

(Cl. D58—8)

To all whom it may concern:

Be it known that I, Robert E. Hennessy, a citizen of the United States, residing at Summit, in the county of Union and State of New Jersey, have invented a new, original, and ornamental Design for a Decanter, of which the following is a specification, reference being had to the accompanying drawing, forming a part thereof.

Fig. 1 is a front elevational view of a decanter, showing my new design;

Fig. 2 is a side elevational view; and

Fig. 3 is a top plan view.

The rear and side views not shown are the same as those shown.

I claim:

The ornamental design for a decanter, as shown and described.

ROBERT E. HENNESSY.
